UNITED STATES PATENT OFFICE

2,471,405

HAIR DRIER

Ralph K. Boyer, Cleveland, Ohio, assignor to Designers for Industry, Inc., Cleveland, Ohio, a corporation of Ohio

Application July 10, 1947, Serial No. 760,049

18 Claims. (Cl. 34—100)

1

This invention relates to hair drying apparatus and more particularly to driers of the type adapted to be fitted about the head of an individual for effecting drying of the hair after shampooing, setting, or the like.

An object of the invention is to provide a novel and improved construction for a hair drying apparatus, which has a power driven air impeller for circulating air about the head of an individual, whereby the impeller and driving means therefor may be easily and quickly removed as a unit from the remainder of the apparatus.

Another object of the invention is to provide a novel and improved hair drier, which has a power driven air impeller for causing air to flow about the head of an individual, with improved means for directing the flowing air about and through the individual's hair.

A further object of the invention is to provide a novel and improved hair drier, which has a power driven air impeller for causing air to flow about the head of an individual, with means whereby an adjustable amount of the flowing air may be recirculated within the drier and about the individual's head.

A more specific object of the invention is to provide a novel and improved hair drier, which has a power driven air impeller for causing air to flow about the head of an individual, with an adjustable damper whereby an adjustable amount of the air may be recirculated within the drier and about the individual's head.

It is also an object of the invention to provide a novel and improved hair drier with an improved power driven air impeller which is so constructed as to produce both an axial and a radial movement of the air within the drier.

The invention further resides in certain novel features, details of construction, combinations and arrangements of parts, and further objects and advantages thereof will be apparent to those skilled in the art to which it pertains from the following description of the present preferred embodiment thereof, described with reference to the accompanying drawings in which similar reference characters represent corresponding parts throughout several views, and in which:

Fig. 1 is a sectional view, taken substantially vertically through the longitudinal axis of a hair drier constructed in accordance with this invention, with certain portions broken away and others shown in elevation;

Fig. 2 is a sectional view taken substantially on the section line 2—2 of Fig. 1;

Fig. 3 is a fragmentary sectional view taken substantially on the section line 3—3 of Fig. 1;

Fig. 4 is a sectional view taken substantially on the section line 4—4 of Fig. 1;

Fig. 5 is a fragmentary sectional view corre-

2

sponding to Fig. 1 but showing certain of the parts thereof in a different operative position;

Fig. 6 is a longitudinal sectional view similar to Fig. 1, with certain parts broken away, and indicating the direction of air circulation within the drier when the adjustable damper thereof is in one position;

Fig. 7 is a sectional view similar to Fig. 6 and illustrating the circulation of air within the drier when the damper thereof is in a different position; and,

Fig. 8 is a developed, elevational view of the inner shell or conduit of the drier, looking from the center line thereof outwardly and with the front edge of the conduit at the top of the figure, illustrating the air circulating openings therein and the positions of the air directing vanes attached thereto.

The hair drier illustrated in the drawings, as the present preferred embodiment of this invention, is of the pedestal type adapted to be positioned about the head of an individual to effect drying of the hair after shampooing, setting or like operations. This drier comprises an ogivally shaped head or shell, generally designated 10,

which is pivotally mounted on a conventional pedestal or bracket 11. The head or shell of the drier forms a housing for the drier mechanism and is preferably composed of any relatively rigid thin material, such as sheet metal or the like, constructed in two pieces consisting of a forward portion 12 and a rear portion 13. The forward portion 12 of the shell is provided with one or more downwardly projecting ears 11a for receiving a pivot pin or bolt 14 which is fitted in a transversely extending bore adjacent the upper end of the pedestal or bracket 11.

The rear portion 13 of the shell is detachably connected with the forward portion 12 by one or more suitable securing means, generally designated 15, the abutting edges of the two portions of the shell preferably being rabbeted to facilitate alignment and provide a substantially air-tight joint. In the present embodiment the securing means are illustrated as being of the type commonly employed as latches upon luggage trunks. Three such latches or securing means are employed and each includes a substantially hook-shaped portion 16, welded or otherwise connected to the front portion 12 of the shell; and an operating handle 17 pivotally mounted upon the rear portion 13 of the shell and having a loop portion 18 adapted to be engaged about the hook-shaped portion 16. As will be readily understood, movement of the handles 17 through an arc of approximately 90 degrees, from the positions shown in Figs. 1, 6 and 7, will enable the loops 18 to be released from the hook-shaped portions 16 of the latches so that the rear

portion 13 of the head or shell may be readily

removed from the forward portion 12 which remains supported by the pedestal 11.

Disposed within the rear portion 13 of the head or shell is an electric motor 19 with its longitudinal axis substantially coinciding with the axis of the shell or head. The rear portion of the motor is supported by means of a centrally located hollow boss 20, provided with a resilient bushing 21, and positioned in the latter is a projecting cylindrical portion 22 of the motor. This portion 22 is illustrated as being the end of the armature shaft but it will be readily understood that a reduced diameter extension of the housing for the motor may be similarly supported if the armature shaft does not project beyond the rear of the housing. The forward end of the motor is supported by spaced brackets 23, the outer ends of which are connected by screws 24 to an integral ring or spaced bosses 25 provided in the rear portion 13 of the shell. The upper or inner ends of the brackets 23 are connected, as by means of welding or the like, to an annular plate or bushing 26 having a central opening therethrough within which is positioned a resilient bushing substantially conforming with the shape of the housing of the motor at this point.

The forward end of the shaft 22 of the motor is provided with an air impeller or fan, generally designated 27. This impeller or fan is provided with a plurality of substantially propeller-shafted portions or blades 28, the outer ends of which are connected by a ring portion 29 having an upstanding cylindrical flange 30. Preferably the blades 28, the ring 29 and the flange 30 are formed from a single piece of sheet metal but these parts may be separately formed and united by welding or similar means to provide an integral unit. Attached at spaced points to the outer periphery of the cylindrical portion 30 of the air impeller are radially extending blower portions or blades 31, the lower ends of which are shown as provided with flanges which are attached by welding or the like to the cylindrical portion 30. The construction of the air impeller is such that when the motor is driven in a clockwise direction, as viewed in the drawings, the blades 28 of the fan will tend to produce an axial flow of the air from the front of the drier to the rear thereof while the blades 31 will impart a radial and circular motion to the air adjacent the inner surface of the shell or housing of the drier.

The rear portion 13 of the outer shell of the drier is provided with another internal flange or spaced bosses 32 to which is connected a tubular member or cylindrical sleeve 33, extending coaxially with respect to the motor 19 and having a diameter intermediate the diameters of the blades 28 and of the flange 30 of the air impeller 27. Positioned within this tubular member or sleeve 33 is a cylindrical damper or shutter 34, which is preferably formed of relatively thin sheet metal. This shutter or damper has a sliding fit within the member or sleeve 33 and is movable from a position in which its outer edge is closely adjacent the ring portion 29 of the air impeller, as shown in Figs. 1 and 6, to a position in which its outer edge is closely adjacent the outer edge of the sleeve 33, as shown in Figs. 5 and 7.

Movement of the shutter or damper 34 is effected by means of a manually operable rod 35 which extends through a boss 36 at the rear of the portion 13 of the head or shell 10, the rod being

provided at its outer end with its knob or handle 37 by which it may be grasped and operated. The portion of the rod 35 within the shell or housing is operatively connected with the shutter or damper 34 by welding or securing the rod to a polygonally shaped bracing member 38, see Fig. 3, the corners of which engage the inner surface of the shutter or damper 34 and are secured thereto. This bracing member reinforces the damper and enables the latter to be easily moved longitudinally within the sleeve 33 by means of the single actuating rod 35, the damper being movable to either extreme position thereof or to any intermediate position that may be desired for a purpose hereinafter described.

Adjacent the rear edges of the radial blades 31 of the fan or impeller 27, the portion 13 of the housing or shell 10 is provided with an integral flange or spaced bosses 39 to which an annular member 40 is attached by means of screws or the like 41. This member 40 has an inwardly direct ing portion 42 substantially conforming with the rear edges of the blades 31 but spaced therefrom, this portion of the member 40 then merging with a substantially cylindrical portion 43 which extends concentrically with respect to the sleeve 33 and damper 34 but spaced outwardly therefrom. The inner surface of this cylindrical portion 43 of the member 40 is provided with a plurality of spaced mounting means or lugs 44 which are bolted or otherwise attached to the cylindrical portion of the member. These lugs or mounting means are provided with transversely extending openings through which extends an electrical heating element 45, the lugs or mounting means 44 being either formed of insulating material or provided with insulated inserts so that the heating means 45 is insulated from the member 40.

The front portion 12 of the housing or shell 10 has its forward edge curved inwardly slightly as indicated at 46 to provide a suitable opening into which the head H of an individual may be inserted to dispose the hair thereof within the confines of the drier, the curved portion 46 also serving to direct air about the hair, as hereinafter described. Concentrically positioned within the front portion 12 of the outer shell is a conduit or inner shell portion 47 substantially cylindrical in configuration and having a diameter sufficient to receive the head of an individual, as indicated in Fig. 1. The diameter of the conduit or inner shell 47 is less than that of the outer shell portion 12 thus providing an annular air passage therebetween. The forward edge of the conduit is spaced inwardly from the edge of the forward portion 46 of the outer shell, the latter being so shaped as to direct air flowing past the outer edge of the conduit into the interior thereof.

This conduit or inner shell portion 47 is supported within the outer shell by a plurality of circumferentially spaced, longitudinally extending members or vanes 48. These members or vanes have lower flange portions 49, which are welded, or similarly secured, to the outer periphery of the conduit or inner shell 47, and side portions 50 extending angularly outwardly from the exterior surface of the conduit 47 and into engagement with the interior of the outer shell portion 12. The outer edges of the vanes 48 are shaped to substantially conform with the interior curved surface of the outer shell thus securely retaining the conduit or inner shell in its proper position by the frictional engagement between the outer edges of the vanes and the portion 12 of the outer shell. However, the outer edges of the vanes 48

may be welded or otherwise secured to the outer shell if desired. As will be seen in Fig. 2, these members or vanes extend in a generally counter-clockwise direction for a purpose hereinafter described.

The upper portion of the conduit or inner shell 47 is provided with a plurality of circumferentially spaced openings 51 and 52 to permit air to flow therethrough over the back of the individual's head, the openings being located so that the air enters the interior of the conduit 47 at approximately the mid point of the individual's head positioned therein. The openings 51, adjacent the top of the conduit, are substantially triangular and in the present embodiment three such openings are provided. The openings 52, further around the conduit, are substantially trapezoidal in shape and two such openings are employed in the present construction. These openings are each disposed beneath one of the vanes 48 with one side of each opening closely adjacent the point of connection of the corresponding vane to the conduit 47, the configurations and disposition of the openings and vanes being clearly indicated in Fig. 8 of the drawings which is a developed view of the conduit or inner shell 47 looking from the center line thereof outwardly and with the forward edge of the conduit disposed at the top of the figure. As will be seen from Figs. 1 and 8, the axial lengths of the vanes 48 vary, the longest vanes being adjacent the openings at the left side of the drier, as viewed from the front, and the shortest vanes being at the bottom of the drier.

The construction is such that the air, which is circulated by the radial blades 31 of the impeller 27, is moving in a clockwise direction and forwardly within the annular space between the outer and inner shells, the clockwise movement of the air being prevented in the forward portion of the drier by the vanes 48 which tend to straighten the flow of the air and direct a portion thereof through the openings 51 and 52 into the interior of the conduit 47. The remainder of this air passes forwardly of the drier and is directed by the inwardly curved outer edge 46 of the outer shell to flow backwardly over the head of the individual from points adjacent the hairline. Since, as previously mentioned, the air tends to circulate clockwise about the conduit 47, except as prevented by the vanes 48, a greater proportion of the air would be directed through the openings 51 and 52 at the right side of the drier as, viewed from the front, than at the left side thereof if the vanes were all of the same length. By proportioning the vanes and openings substantially as shown, a substantially uniform distribution of airflow may be secured.

To further assist the flow of air through the openings 51, circumferentially extending vanes 53 are provided adjacent the forward edges of the openings 51. These vanes 53 have lower flange portions 54, welded or otherwise connected to the outer periphery of the conduit 47 adjacent the openings 51, and inclined side portions extending upwardly and rearwardly with their outer edges conforming in shape with and engaging the interior surface of the outer shell of the drier. The edges of the side portions of these vanes 53, at their point of contact with the corresponding vanes 48, are provided with flange portions 55 which are welded or otherwise secured to the vanes 48 as indicated in Figs. 1, 2 and 8. Therefore, a substantial portion of the air moving forwardly between the upper vanes 48 is deflected

by the vanes 53 into the openings 51. However, the vanes 53 do not completely obstruct the forward flow of air at this point of the drier since the circumferential extent of the vanes 53 is only approximately one-half the distance between adjacent vanes 48.

The conduit or inner shell portion 47 has an inwardly directed annular shoulder 56 from which a substantially cylindrical sleeve-like portion 58 10 extends rearwardly as shown in Figs. 1, 5, 6 and 7. The diameter of this rearwardly extending sleeve portion 58 is intermediate the diameter of the propeller blades 28 and the diameter of the portion 30 of the air impeller, with the outer edge of the sleeve 58 extending adjacent to but slightly spaced from the annular portion 29 of the impeller. As shown in Figs. 1, 5, 6 and 7, this construction allows a portion of the propeller blades 28 to extend within the sleeve portion 58 of the conduit or inner shell member 47 while the outer or radial blades 31 of the impeller are disposed exteriorly of this sleeve portion. Hence, the effects of the blade portions 28 and 31 are substantially restricted to the interior and exterior, respectively, of the conduit. Extending across the central opening in the sleeve portion 58 of the conduit 47 is a foraminous material 59 20 such as wire mesh or the like, which is secured to the shoulder 56 by suitable means such as a ring member 60. If desired, the ring member 60 may include a grill portion extending over the mesh material 59 to provide support for the latter intermediate its edges. This mesh material prevents the hair of the individual from being drawn into the rear portion of the drier where it would become entangled with the air impeller.

The rear portion 13 of the drier shell is provided with a plurality of spaced openings 61 and 62 30 providing air vents. It will be observed that the openings 61 are positioned within the confines of the tubular or cylindrical member 33 and hence communicate with the interior of the conduit 47, thus providing air exhausting vents for the drier. The openings 62 are positioned outside of the tubular member 33 and communicating with the space between the outer shell and the conduit, thus forming air intake openings for the drier. The openings are preferably covered by material such as wire mesh or the like 63 and 64, respectively. This material may be applied only over the openings 61 and 62 per se or, if desired, may extend in parallel bands about the entire circumference of the drier, suitable recesses being then provided in the outer surface of the shell, intermediate the openings, to retain such bands in position.

Electrical cables, not shown, extend through suitable openings in the rear portion 13 of the outer shell or housing for connection with the motor 19 and the heat element 45 and suitable switches and controls of conventional type may be inserted in such cables at convenient points to control the operation of the motor and the heater respectively.

When it is desired to quickly dry the hair of an individual after shampooing or the like, the drier is positioned about the individual's head H in the manner shown in Fig. 1. The motor 19 is then placed in operation and current is supplied to the heating means 45. The handle or knob 37 of the rod 35 is moved inwardly of the shell to its extreme inner position thus moving the inner edge of the shutter or damper 34 to its position as shown in Figs. 1 and 6. There is thus provided a substantially closed passageway from

the cylindrical sleeve portion 58 of the conduit 47 through the shutter or damper 34 to the rear of the housing. Since the motor 19 rotates the impeller 27 in a clockwise direction, a suction or partial vacuum will be created in front of the propeller-type blades 28 thus drawing air from the interior of the conduit 47 and hence from about the head of the individual, the major portion of the air exhausting through the openings 61 at the rear of the housing.

Since the individual's head substantially closes the opening at the front of the drier, only a small amount of air will be drawn inwardly adjacent the curved edge 46 of the outer shell of the drier. The majority of the air, to replace that which is exhausted from the interior of the conduit 47, enters the drier through the openings 62 at the rear of the outer shell and passes over the heating element 45 thereby increasing its dehydrating effect. This air then passes through the radial blades 31 of the impeller which imparts a radial and circular motion to the air causing it to move forwardly through the annular space between the conduit or inner shell 47 and the forward portion 12 of the outer shell. This circulating air strikes the side portions 50 of the vanes or deflector members 48 which tend to straighten the flow of the air and direct a portion thereof through the openings 51 and 52, the vanes 53 aiding in this latter directing of the air. The air entering the openings 51 and 52 strikes the hair at substantially the midpoint thereof and, as indicated by the arrows in Fig. 6, will be circulated thereabout and exhausted at the rear of the drier by means of the propeller-shaped blades 28.

The remainder of the air flowing through the stationary vanes or members 48, which does not enter the openings 51 and 52, is directed by the curved forward edge 46 of the drier so as to flow backwardly over the individual's head from adjacent the hairline thereof and, after circulating about the hair, will likewise be exhausted by the impeller 27 through the openings 61. Only a small part of the air circulating rearwardly through the conduit passes through the relatively small space between the sleeve portion 58 of the conduit 47 and the forwardly positioned shutter 34 to re-enter the annular space between the members 47 and 12 for recirculation. Hence, a large volume of fresh, relatively warm dry air is continuously supplied to the hair which is therefore rapidly dried.

When relatively slow drying is desired as, for example, after the hair has been set, the handle or knob 37 is pulled outwardly with respect to the drier head or shell thus causing the rod 35 to move the shutter or damper 34 from the position shown in Figs. 1 and 6 to its extreme open position as indicated in Figs. 5 and 7. When the motor 19 is now placed in operation, the propeller-shaped blades 28 of the impeller 27 again create a partial vacuum or suction within the interior of the conduit or inner shell 47, thus causing air to flow into the interior of the conduit through the openings 51, 52 and from the forward portion 46 of the outer shell, as indicated by the arrows in Fig. 7. A major portion of the air exhausted by the propeller-shaped blade portions of the impeller is now, however, recirculated through the drier by passing through the relatively large opening between the rear edge of the sleeve portion 58 of the conduit and the forward edge of the shutter or damper 34, only a relatively small portion of the air being exhausted through the openings 61 at the rear of

the housing. This flow of air through the space between the shutter or damper and the cylindrical portion of the conduit is caused in part by the positive action of the propeller-shaped blades 28 and by the action of the radial blades 31 but is also assisted by the pressure gradient created by the relatively high velocity flow of air within the annular space between the conduit and outer shell. When the apparatus is so operated, the heating means 45 may be regulated to produce the desired amount of heat by suitable controls, not shown.

The rate of drying of the hair may be closely controlled by positioning the damper 34 at any desired position intermediate the two extremes just described and/or by adjustment of the amount of heat applied by the heating means 45. The adjustment of the damper or shutter 34 thus enables any desirable portion of the air to be recirculated within the drier or substantially the entire flow of air may be exhausted exteriorly of the drier without recirculation, as previously described.

The construction of the drier head in two separable portions 12 and 13 enables the drier to be more easily serviced since it is only necessary to release the securing means or latches 15 when it is desired to gain access to the motor, impeller, damper and heater, these elements being all supported in the rear portion 13 of the head independently of the conduit or inner shell 47 and the vanes 48 and 53. Hence, the moving parts of the mechanism can be easily and quickly removed as a unit thus facilitating servicing since these parts are more easily accessible and it is no longer necessary to remove the entire drier from the pedestal. Furthermore, a different rear portion 12 may be placed upon the drier in substitution for the one removed so that the use of the drier need not be interrupted for any appreciable length of time while the original mechanism is being serviced.

While a preferred embodiment of the hair drier of this invention has been described in considerable detail it will be appreciated that numerous modifications and variations in the construction may be effected without departing from the spirit of the invention. Thus the location and shapes of the openings 51, 52, and of the vanes 48 and 53, may be varied as desired, as may also the shape of the impeller blades and the mode of mounting and operating the shutter or damper 34. Other variations and adaptations of the invention will readily suggest themselves to one skilled in the art and therefore the invention is not to be considered as limited to the exact details of construction and mode of operation herein illustrated and described but only as required by the spirit and scope of the appended claims.

Having thus described the invention, I claim:

1. In a hair drier of the character described, a housing having inner and outer shells defining substantially coaxial passages, said housing having a front opening adapted to receive a portion of a head of hair to be treated and said passages communicating adjacent said front opening and also communicating at a point spaced from said front opening so as to provide a path for circulating air within the housing for contact with said hair, the said outer shell having spaced openings therethrough, air flow creating means including a rotor having air impelling portions operable to produce air circulation in the respective coaxial passages, and an adjustable flow controlling

means intermediate said shells for controlling the second-mentioned communication between said passages, the said air flow controlling means including a portion for channeling the flow of air from at least one of the openings in the outer shell to one of said passages and the flow of air through the other of said passages to a different one of said openings in the outer shell.

2. A hair drier as defined in claim 1, and further comprising a heating element in one of said passages for heating the air passing therethrough.

3. A hair drying apparatus of the character described comprising a conduit adapted to have its forward end positioned about the head of an individual, a shell surrounding the sides and rear end of said conduit in spaced relationship thereto, the said shell having spaced openings therethrough adjacent the rear end thereof, an air impeller positioned in said shell adjacent the rear end of the conduit and having portions to induce a flow of air through the latter, said air impeller having other portions to induce a flow of air in the space between said conduit and said shell, means to rotate said air impeller, means for deflecting a portion of the air flowing in said space between said conduit and said shell into the interior of said conduit intermediate its ends, and means adjustable towards and away from the rear end of said conduit to regulate the flow of air between the latter and the space between said conduit and said shell and to channel the flow of air from certain of the openings in said shell to said space and from said conduit to others of said openings.

4. A hair drying apparatus of the type defined in claim 3 and further comprising a heating means mounted within said shell for heating the air flowing through the space between said conduit and said shell.

5. A hair drying apparatus of the character described comprising a conduit adapted to have its forward end positioned about the head of an individual, a shell surrounding the sides and rear end of said conduit in spaced relationship thereto, the said shell having openings at the rear thereof for admitting air to the space between said conduit and shell and for exhausting air from the interior of the conduit, an air impeller positioned in said shell adjacent the rear end of the conduit and having portions to induce a flow of air through the conduit from the front to the rear thereof, said air impeller having other portions to induce a flow of air forwardly through the space between said conduit and said shell, means to rotate said air impeller, means for deflecting a portion of the air flowing in said space between said conduit and said shell into the interior of said conduit intermediate its ends, the forward end of said shell extending beyond the forward end of said conduit and having a portion shaped to deflect the remainder of the air flowing between the conduit and shell into the forward end of said conduit, and hollow damper means having its interior communicating with at least one of the said openings in the rear of said shell, the said damper means including a movable sleeve portion for regulating the flow of air between the rear end of said conduit and the space between said conduit and said shell and for conducting air flowing through said conduit out of said shell.

6. A hair drying apparatus of the character described comprising a conduit adapted to have its forward end positioned about the head of an

individual, a shell surrounding the sides and rear end of said conduit in spaced relationship thereto, the said shell having openings at the rear thereof for admitting air to the space between said conduit and shell and for exhausting air from the interior of the conduit, an air impeller positioned in said shell adjacent the rear end of said conduit and having portions to induce a flow of air through the conduit from the front to the rear thereof, said air impeller having other portions to induce a flow of air forwardly through the space between said conduit and said shell, means to rotate said air impeller, stationary vanes between said shell and conduit for straightening the path of flow of air therebetween and for deflecting a portion of this air into the interior of said conduit through openings in the latter intermediate its ends, the forward end of said shell extending beyond the forward end of said conduit and having a portion for deflecting the remainder of the air flowing between the conduit and shell into the forward end of said conduit, and adjustable means to regulate the flow of air between the rear end of said conduit and the space between said conduit and said shell.

7. A hair drying apparatus of the type defined in claim 6 and further comprising a heating means mounted within said shell for heating the air flowing through the space between said conduit and said shell.

8. A hair drying apparatus of the character defined in claim 6 and in which said shell is formed by two separable portions with the said impeller, the said means to rotate the impeller and the said adjustable means supported in one portion and said conduit and said stationary vanes supported in the other portion of the shell; means for supporting the said other portion of the shell; and means to detachably secure said portions of the shell together; whereby the entire drying apparatus is supported by said supporting means and the impeller, rotating means and adjustable means may be readily removed as a unit without disturbing said supporting means and the remainder of the drying apparatus.

9. A hair drying apparatus of the character described comprising a conduit adapted to have its forward end positioned about the head of an individual, a shell surrounding the sides and rear end of said conduit in spaced relationship thereto, an air impeller positioned in said shell adjacent the rear end of the conduit and having substantially propeller-shaped portions extending into said conduit to induce a flow of air therethrough, said air impeller having substantially radially extending portions connected to the ends of the propeller-shaped portions and extending exteriorly of the conduit to induce a flow of air in the space between said conduit and said shell, means to rotate said air impeller, means for deflecting a portion of the air flowing in said space between said conduit and said shell into the interior of said conduit intermediate its ends, and an adjustable damper at the rear of said impeller and adapted to be positioned closely adjacent the rear of the latter intermediate the propeller-shaped portions and the radial portions thereof to substantially prevent the flow of air between the rear end of said conduit and the space between said conduit and said shell, and to be spaced rearwardly of the impeller to permit flow of air between the rear end of said conduit and the space between said conduit and said shell.

10. A hair drying apparatus of the character described comprising a substantially tubular con-

duit adapted to have its forward end positioned about the head of an individual, a shell surrounding the sides and rear end of said conduit in spaced relationship thereto, the said shell having openings at the rear thereof for admitting air to the space between said conduit and shell and for exhausting air from the interior of the conduit, a substantially tubular member spaced rearwardly of said conduit and substantially coaxial therewith, the rear portion of said tubular member being connected to the interior of said shell in a manner to surround the openings in the latter for exhausting air from said conduit, an air impeller positioned in said shell adjacent the rear end of the conduit and spaced forwardly of the forward end of said tubular member, said air impeller having portions to induce a flow of air through the conduit from the front to the rear thereof and having other portions to induce a flow of air forwardly through the space between said conduit and said shell, means to rotate said air impeller, a substantially tubular damper slidably supported by said tubular member and movable to a position closely adjacent the rear of the air impeller intermediate the first and second mentioned portions thereof to substantially prevent the flow of air between the rear end of said conduit and the space between said conduit and said shell, and to be spaced rearwardly of the impeller to permit flow of air between the rear end of said conduit and the space between said conduit and said shell and means connected with said damper and extending exteriorly of the shell for adjusting the position of said damper.

11. A hair drying apparatus of the type defined in claim 10 and in which the forward end of said shell extends beyond the forward end of said conduit and has a portion shaped to deflect the air flowing between the conduit and shell into the forward end of said conduit.

12. A hair drying apparatus of the type defined in claim 10 and further comprising means for deflecting a portion of the air flowing in said space between said conduit and said shell into the interior of said conduit intermediate its ends, and the forward end of said shell extends beyond the forward end of said conduit and has a portion for deflecting the remainder of the air flowing between the conduit and shell into the forward end of said conduit.

13. A hair drying apparatus of the type defined in claim 10 and further comprising a heating means mounted within said shell for heating the air flowing through the space between said conduit and said shell.

14. A hair drying apparatus of the type defined in claim 10 and in which the said tubular damper is slidably supported upon the interior surface of said tubular member, and a polygonally shaped member is secured to the interior of said damper to reinforce the latter.

15. A hair drying apparatus of the character described comprising a conduit adapted to have its forward end positioned about the head of an individual, a two-part separable shell surrounding the sides and rear end of said conduit in spaced relationship thereto with the said conduit supported in one part of the shell, an air impeller supported in the other part of said shell adjacent the rear end of the conduit, the said impeller having portions to induce a flow of air through the

conduit and other portions to induce a flow of air in the space between said conduit and the said one part of the shell, means supported in the said other part of the shell and connected with said air impeller to rotate the latter, means in said one part of the shell for deflecting a portion of the air flowing in said space between said conduit and said one part of the shell into the interior of said conduit intermediate the ends of latter, adjustable means supported in said other part of said shell for regulating the flow of air between the rear end of said conduit and the said space between the conduit and shell, means for supporting said one part of said shell, and means to detachably secure the two parts of said shell together, whereby the entire drying apparatus is supported by said supporting means, and the impeller, rotating means and adjustable means may be readily removed as a unit without disturbing said supporting means and the remainder of the drying apparatus.

16. A hair drying apparatus of the character described comprising a shell-like member adapted to have its forward end positioned about the head of an individual, a two-part separable housing surrounding the sides and rear of said member in spaced relationship with the said member supported in one part of said housing and with the space between said member and housing in communication with the interior of said member, an air impelling means supported in the other part of said housing adjacent the rear of said member for circulating air within said housing and member, means for supporting said one part of said housing, and means to detachably secure the two parts of said housing together, whereby the entire drying apparatus is supported by said supporting means with the said other part of said housing and the air impelling means readily removable as a unit without disturbance of said supporting means or the remainder of the drying apparatus.

17. A hair drying apparatus as defined in claim 16 and further comprising adjustable means for controlling the circulation of air within said housing, and means supporting the last-mentioned means in the said other part of said housing whereby the said adjustable means is removable with said air impelling means upon release of the said means for securing together the two parts of the housing.

18. A hair drying apparatus as defined in claim 16 and further comprising a heating means mounted within said other part of said housing for heating air circulated by said air impelling means.
